UNITED STATES PATENT OFFICE.

ALFRED T. STURT, OF NEW YORK, N. Y., ASSIGNOR TO GENERAL MOTORS CORPORATION, OF DETROIT, MICHIGAN, A CORPORATION OF DELAWARE.

SPRING BRACKET.

1,419,083.

Specification of Letters Patent. Patented June 6, 1922.

Application filed April 8, 1920. Serial No. 372,198.

To all whom it may concern:

Be it known that I, ALFRED T. STURT, a citizen of the United States, and a resident of New York, county of New York, and 5 State of New York, have invented certain new and useful Improvements in Spring Brackets, of which the following is a full, clear, concise, and exact description, such as will enable others skilled in the art to which 10 the invention relates to make and use the same, reference being made therein to the accompanying drawings, which form a part of this specification.

My invention relates to spring mechanism 15 associated with and forming a part of automobiles and similar self-propelled vehicles, and particularly to spring mechanism in which leaf springs are employed for supporting the frame and body of the vehicle 20 from the axles thereof.

The principal object of my invention is to provide an improved supporting member or device for securing the fixed ends of the leaf springs whereby the vehicle body is 25 supported to the side members of the vehicle frame, and with which supporting devices the free ends of the several separate springs in question are secured.

A further object of my invention is to 30 provide certain new and useful improvements in and relating to supporting members or brackets whereby and through which the fixed ends of the frame and body supporting springs are secured to the frame of the vehicle.

A further object of my invention is to 35 provide improved spring supporting means for the fixed ends of the springs whereby the vehicle body is supported, and in which 40 supporting means the bolts commonly employed to secure the spring in place will not be subject to tension or other strains due to the weight of the vehicle body; the stress due to the weight borne by the springs being taken up by fixed abutments which form 45 a part of the supporting means in question.

With the above and other objects of invention in view, my invention consists in the improved supporting means for the fixed 50 ends of vehicle springs where they are secured to the side frame members of the vehicle illustrated in the accompanying drawing and hereinafter described and claimed; and in such variations and modifications 55 thereof, within the scope of the concluding

claims, as will be obvious to those skilled in the art to which my invention relates.

Referring now to the drawing wherein the preferred embodiment of my invention is 60 illustrated:

Figure 1 is a view showing a leaf spring in perspective and the forward end of which is secured to one of the side frame members of the vehicle frame by the use of supporting means made in accordance with my invention, the spring illustrated being one of two springs which support the rear end of the vehicle body.

Figure 2 is a perspective view showing one of my improved supporting devices or 70 brackets for the fixed end of the springs as seen from a position beneath the same.

Figure 3 is a perspective view showing one of the front leaf springs which support the vehicle body, the rear fixed end thereof 75 being secured to a side bar of the frame of the vehicle by means of a supporting device made in accordance with my invention.

Referring first to Figure 1, the reference numeral 4 designates one of the two side 80 members of the frame of the vehicle, the same being commonly channel-shaped in cross section as shown; and the spring designated by the reference numeral 5 may be made up of a plurality of leaves assembled 85 one on top of another and which leaves are shown as secured together by clips 6. The spring shown is of the type commonly referred to as a half-semi-elliptic spring, and the rear end thereof is secured to a bracket 90 7 as by means of the rearmost clip 6 and a bolt 8, and which bracket 7 is provided with a cylindrical bearing through which the housing of the rear axle of the vehicle extends.

The front end of the spring 5 is secured to the frame member 4 by a fixed end supporting device made in accordance with my invention, said device being in the general 100 form and performing the functions of a bracket and the same having one or more flanges 9, 10, adapted to be secured to the side frame member by means of bolts, rivets or like fastening devices; although the form of said flanges may be varied within wide 105 limits without departing from my invention as my invention, considered in its broader aspect, is regarded as including any type or kind of flange or flanges whereby the fixed end supporting device or bracket may be se- 110

cured to a side member of the frame of the vehicle.

My improved spring supporting device is provided with a housing formed integrally 5 therewith and the form of which may vary, but which housing is illustrated as having oppositely disposed depending side walls or webs 11, 11, and an end wall or web 12 which is so disposed as to partially close the 10 forward open end of the housing illustrated in Figure 1. Said housing is also provided with a top wall 13 which in effect is a continuation of the horizontal fastening flange 10 and with a bottom wall 14 extending be- 15 tween the side walls and which forms an abutment or ledge against which the under side of the extremity of the spring 5 bears, and by which flange the said extremity is supported when the end of the spring is in- 20 serted into the hollow housing made up of the elements above referred to. The top wall 13 is provided with a second abutment 15 upon its under side and which abutment is spaced apart in the direction of the length 25 of the spring from the lower abutment 14, and against which upper abutment the upper side of the spring 5 bears when the free end of said spring is in position within the housing for receiving the same.

30 In view of the premises it will be appreciated that when the free end of a spring like the spring 5 is in place within the housing provided for its reception a downwardly acting force will be communicated to the 35 spring through the abutment 15 which contacts with the upper surface thereof at a point some little distance from the extreme end of the spring. At the same time downward movement of the extremity of the 40 spring will be prevented by the abutment 14, which contacts with the under side of the spring at the extreme end thereof; thus providing a spring support in which the 45 stresses set up by the load upon the vehicle results in compression forces only in the supporting member or bracket at the fixed end of the spring.

It therefore follows that so far as static forces are involved the body of the vehicle will be supported from the springs without the use of fastening bolts associated with the supporting means in question. I prefer, however, to provide a bolt 16 at the 50 extremity of the spring and extending 55 through holes in the leaves thereof, and through a hole 17 in the lowermost abutment 14, the head of said bolt lying in a recess provided for it in the upper wall 13 of the housing, so that in tightening the 60 said bolt the leaves of the spring will be drawn toward the lowermost abutment 14. It will be appreciated, however, that the weight borne by the frame of the vehicle will not subject the bolt 16 to tension, and 65 that the real effect of the bolt in question

is to prevent displacement of the inner extremities of the spring. Other bolts 18 are also provided which extend through holes 19 provided in the top walls 13 of the housing and the lower ends of which bolts extend through holes provided in the ends of a cross bar or clip 20 which lies beneath the spring and acts, when the bolts are tightened, to force the spring upward and hold the same in firm engagement with the uppermost abutment 15 above referred to.

In the form of my invention illustrated in Figure 3 the spring 21 is one of the two oppositely located springs whereby the forward end of the body is supported from the forward axle 22 of the vehicle, the extremities of the springs being secured to the axle by a bolt 23 and a clip 24 or otherwise. The fixed end of the spring 21 extends into a housing made up of top, side and bottom 85 walls of substantially the same form as in the form of my invention illustrated in Figures 1 and 2, the under side of the extremity of the spring being supported by a ledge in all essential particulars like the ledge 14; 90 while the upper surface of the spring abuts against an upper abutment in all respects like the abutment 15 hereinbefore referred to. The end of the spring in this form of my invention is held in place within the 95 housing by bolts in the same way as hereinbefore explained, and the bracket as a whole whereby the fixed end of the spring is supported is provided with suitable flanges, one of which is indicated by the reference 100 numeral 25, whereby the spring support may be secured to the side member 5 of the vehicle frame.

It will be appreciated that while the spring supporting device or bracket illustrated in Figure 2 is in a sense referred to as the same one that is shown in Figure 1, the bracket shown in Figure 2 is in fact the bracket which is secured to the frame member opposite the frame member 4 and supports the 110 fixed end of the other of the two springs whereby the rear end of the frame is supported; the two spring supporting brackets in question being alike except that one is a "right" and the other a "left" designed 115 to be secured one to the right and the other to the left hand side bars of the frame of the vehicle.

Having thus described and explained my invention, I claim and desire to secure by 120 Letters Patent:

1. Fixed end supporting means for automobile springs comprising a unitary single piece bracket provided with a flange whereby it may be secured to a frame member, and a housing adapted to receive and hold the fixed end of a leaf spring; said housing having an abutment or ledge at its lower end whereby the under side of the extremity of a spring may be supported, and a second 130

abutment at its upper end spaced apart from said first mentioned abutment and against which the upper side of a spring may bear; and bolts adapted to force the extremity of a spring downward and against said first mentioned abutment, and to force another portion of a spring spaced apart from its extremity upward and against said second mentioned abutment, whereby stresses due to the load borne by the spring are resisted by said abutments and said bolts are free from said stresses when the device is in use.

2. Fixed end supporting means for automobile springs comprising a unitary single piece bracket provided with a flange whereby it may be secured to a frame member; said bracket having an abutment or ledge at its lower end whereby the under side of the extremity of a spring may be supported, and a second abutment located above and spaced apart from said first mentioned abutment and against which the upper side of a spring may bear; and means for holding the free end of a spring in engagement with said abutments; said abutments acting to resist stresses due to the load borne by the spring, and said holding means being free from said stresses when the device is in use.

3. Fixed end supporting means for automobile springs comprising a unitary single piece bracket provided with a flange whereby it may be secured to a frame member and having an abutment or ledge at its lower end whereby the under side of the extremity of a spring may be supported; a bolt extending through a hole in said abutment and adapted to hold the free end of a spring in engagement therewith; a second abutment located above and spaced apart from said first mentioned abutment and against which the upper side of a spring may bear; and means for forcing the upper side of spring against said last mentioned abutment; said abutments acting to resist stresses due to the load borne by the spring, and said bolt and forcing means being free from said stresses when the device is in use.

4. Fixed end supporting means for automobile springs comprising a unitary single piece bracket provided with a flange whereby it may be secured to a frame member, and a housing adapted to receive and hold the fixed end of a leaf spring; said bracket having an abutment or ledge at its lower end whereby the under side of the extremity of a spring may be supported, and a second

abutment at its upper end spaced apart from said first mentioned abutment and against which the upper side of a spring may bear; and means independent of said abutments 60 and free from stresses due to the load borne by the spring for holding the fixed end of a spring in place within said housing.

5. Fixed end supporting means for automobile springs comprising a unitary single 65 piece bracket provided with a vertically extending flange whereby it may be secured to a frame member, and a housing adapted to receive and hold the fixed end of a leaf spring and which housing is made up of a top wall, two side walls depending therefrom, and an abutment or ledge extending between the lower ends of said side walls; a second abutment provided upon the under 70 side of said top wall and spaced apart from said first mentioned abutment; a bolt the head of which lies within a recess provided in said top wall, and which bolt extends through a hole provided in said first mentioned abutment; two other bolts extending 75 through holes provided in said top wall adjacent said second mentioned abutment, and which bolts are spaced apart from one another so as to receive a spring between them; and a bar having holes at its extremities 80 through which the lower ends of said last mentioned bolts extend.

6. Fixed end supporting means for automobile springs comprising a unitary single piece bracket provided with a vertically and 90 horizontally disposed flange whereby it may be secured to a frame member, and a housing carried by said bracket and located beneath said horizontal flange and which housing is made up of a top wall, side walls 95 spaced apart from one another and depending from said top wall, and an abutment extending between the lower ends of said side walls; a second abutment provided upon the under side of said top wall and which abutment is spaced apart from said first mentioned 100 abutment; and means for securing fixed ends of a spring in place within said housing with the extremity of the under side thereof resting upon said first mentioned abutment, and a portion of the upper side thereof abutting against said second mentioned abutment, said means being free from 105 stresses due to the load borne by the spring when the device is in use.

In testimony whereof I affix my signature.

ALFRED T. STURT.
